UNITED STATES PATENT OFFICE.

SOLOMON OFFENBACH, OF BRADFORD, PENNSYLVANIA.

SHELF.

Application filed August 2, 1923. Serial No. 655,314.

- This invention relates to an improved electric lamp and seeks, among other objects, to provide a device of this character embodying a stand including an ash tray supported by the stand for convenient use.
- 5 The invention seeks, as a further object, to provide a device of this character wherein the lamp stand will also embody a conveniently located book shelf.
- 10 And the invention seeks, as a still further object, to provide a device wherein the lamp stand will further include a spring clamp for holding papers or the like.
- 15 Other and incidental objects will appear hereinafter.
- In the drawings:
- Figure 1 is a side elevation of my improved lamp,
- 20 Figure 2 is a transverse sectional view on the line 2—2 of Figure 1, looking in the direction of the arrows,
- 25 Figure 3 is a detail elevation particularly showing the book shelf,
- Figure 4 is a detail sectional view on the line 4—4 of Figure 1, and
- 30 Figure 5 is a detail sectional view taken through the ash tray of the device.
- In carrying the invention into effect, I employ a weighted base 10 and fixed to the 35 base is an upstanding tubular post 11 preferably square in cross section. Fitting over the upper end of the post is a collar 12 suitably fixed to the post and adjustable through said collar is a set screw 13. Slidably fitting through the collar is a cylindrical rod 14 extending freely into the post so that said rod may be adjusted vertically upon the post and secured in adjusted position by means of the set screw 13. Secured to the upper 40 end of the rod is a flexible metallic tube 15 which may be formed from a helically wound strip of suitable sheet metal and connected to the free end of said tube is a lamp socket 16 embodying an appropriate switch 17 and carrying a reflector 18 disposed to extend over a light bulb fitted in said socket. Extending upwardly through the post 11, rod 14, and tube 15, are circuit wires 18' connected to the socket 16, the circuit for the lamp being controlled, of course, by the switch 17. As will be appreciated, the tube 15 may be flexed for disposing the light bulb and reflector in the exact position desired and provides a means for adjusting 45 the light auxiliary to the vertical adjustment of the rod 14.
- Brazed or otherwise secured to one side of the post 11 near its upper end is a metal strap forming a loop 19 and detachably supported by said loop is an ash tray 20. 60 This ash tray is provided with a lateral rim 21 and mounted on the rim are cigar holders 22 as well as an appropriate match box holder 23. Mounted upon the side wall of the tray at a point midway between the ends 65 thereof is an inverted U-shaped hook 25 bent to fit in the angle beneath the rim 21. One end of the hook as well as the transverse portion thereof is brazed or otherwise secured to said side wall and to said rim 70 while the opposite end of the hook projects downwardly for engagement through the loop 19. The free end of the hook fits snugly through said loop so that the hook will serve to support the tray while, at the 75 same time, the tray may be readily removed and thus may be conveniently kept clean.
- Brazed or otherwise secured to the side of the post below the loop 19 is a similar loop 26 and supported by said loop is a shelf 27. At its inner longitudinal edge the shelf is provided with a medial depending hook 28 removably engaging through said loop connecting the shelf with the post 11 and extending from the shelf at its outer corners are downwardly converging braces 29. At their lower ends, these braces are appropriately secured to a spring clamp 30 embracing the post 11 and gripping said post for connecting the braces with the post. 80 Thus, the braces will relieve the hook 28 of the major portion of any weight placed upon the shelf and, as will be seen, the shelf provides a convenient rest for a book or the like.
- Brazed or otherwise secured to the lower 85 end portion of the post at the side thereof opposite the loops 19 and 26, is a similar loop 31 and removably engaged at its lower end in said loop is an upstanding spring clamp 32 extending upwardly at the adjacent side of the post. The clamp 32 is preferably bowed longitudinally to engage near its free end with the post so that papers or the like may be inserted between the clamp and post to be held by said spring. It will accordingly be seen that I provide a lamp 90 adapted to not only serve all the purposes of similar lamps but which will also incorporate the convenience of an ash tray, book shelf, and paper clamp. Furthermore, attention is directed to the fact that the pos- 95
- 100

- 110

tion of the ash tray 20, book shelf 27 and spring clamp 32 may be interchanged as desired to thus further enhance the convenience of the device.

5 Having thus described the invention, what is claimed as new is:

As a new article of manufacture, a shelf, a tongue integral with the shelf and depending therefrom intermediate the length of its 10 rear edge and adapted to fit into an eye projecting from a front face of a support, arms formed integral with said shelf and depending from the front of the shelf adjacent its ends, said arms converging downwardly and

rearwardly and having their lower end portions bent to extend in parallel spaced relation to each other and substantially parallel to the plane of said tongue, and a spring clamp having a bridge portion secured against the inner faces of the parallel lower 15 end portions of said arms and having arms extending rearwardly from its bridge portion to firmly grip the support from opposed side faces thereof with the said bridge portion engaging the front face of the support. 20 25

In testimony whereof I affix my signature.

SOLOMON OFFENBACH. [L. S.]
